UNITED STATES PATENT OFFICE.

GEORGE VAN HORNE, OF BOSTON, ASSIGNOR TO MELLEN BRAY, OF NEWTON,
MASSACHUSETTS.

LACING-HOOK FOR BOOTS AND SHOES.

SPECIFICATION forming part of Letters Patent No. 250,018, dated November 22, 1881.

Application filed December 31, 1879.

To all whom it may concern:

Be it known that I, GEORGE VAN HORNE, of Boston, in the county of Suffolk and State of Massachusetts, have invented a new and useful Lacing-Hook for Boots and Shoes, of which the following, taken in connection with the accompanying drawings, is a specification.

My invention relates to the construction of lacing-hooks for boots and shoes and other purposes, and has for its object the production of a cheap but serviceable hook; and it consists in the formation of a lace-hook from a single piece of wire bent to the desired form, and having an outer portion consisting of an eye or loop, a neck to receive the string composed of two strands, a portion to rest upon the material, and two prongs adapted to pierce the material and be clinched thereto, as will be described.

Figure 1 of the drawings is a plan of my improved lacing-hook. Fig. 2 is a front elevation. Fig. 3 is a side elevation. Fig. 4 is a section of two pieces of leather or other material with my improved hook set therein; and Fig. 5 is a plan of the blank after the first bending operation.

In the construction of my improved hook I cut a piece of wire to the proper length and bend it, by the aid of suitable tools, to the form shown in Fig. 5, to form the eye or loop *a*, neck

b, with the two parts of the wire in contact, and the two prongs *c c*, separated, as shown. I then bend the prongs *c c* at right angles to the other parts of the blank, and then bend the neck *b* till the eye *a* is directly over the 35 prongs *c* and parallel, or nearly so, to the part *d*, when, the prongs *c c* having been flattened toward their points, or otherwise sharpened to adapt them to pierce the material, the lace-hook is ready for use, and is applied to the 40 shoe or other article by forcing the prongs *c c* through the material and clinching them, as shown in Fig. 4.

By this construction a very strong and serviceable lace-hook is produced at a very much 45 less cost than any lace-hook heretofore manufactured possessing the same strength and other good qualities.

What I claim as new, and desire to secure by Letters Patent of the United States, is— 50

A lacing-hook made from round wire, having the annular loop or eye, the united shank, the V-shaped spread seat and depending prongs, all substantially as set forth.

Executed at Boston, Massachusetts, this 27th 55 day of December, A. D. 1879.

GEORGE VAN HORNE.
